UNITED STATES PATENT OFFICE

2,350,471

METAL CAR SEAL

William George Newton, Prince Albert, Saskatchewan, Canada, assignor to Albert W. Newton, Biggar, Saskatchewan, Canada

Application January 5, 1942, Serial No. 425,599½

1 Claim. (Cl. 292—324)

My invention relates to improvements in car seals, an object of this invention being to provide a device of the character herewithin described which is formed from a one-piece patterned blank, the blank being struck at one end thereof to form two adjacent dished portions, one of which is designed to cover the other to form a boxing for locking mechanism to be placed therewithin.

A further object of my invention is to provide an improved seal for sealing railway car doors which positively cannot be tampered with without breakage, thus revealing the fact that it has been tampered with.

A further object of my invention is to provide a unique form of housing to contain the sealing mechanism.

A further object of my invention is to provide a device of this character which is economical to manufacture and reliable in operation.

With the above more important objects in view and such other minor objects as may appear as the specification proceeds, my invention consists essentially in the arrangement and construction of parts all as hereinafter more particularly described, reference being had to the accompanying drawing, in which:

Figure 1 is a perspective illustration of my improved metal seal and ribbon.

Figure 2 is a cross-section.

Figure 3 is a plan view of my one-piece patterned blank after striking the dished portions therewithin.

Figure 4 is a side view of a portion of my blank after the two dished portions have been struck.

Figure 5 illustrates the manner in which the endmost dished portion is bent over to form a housing with the inner dished portion.

Figure 6 illustrates the manner in which the ribbon proceeds through the endmost dished portion.

In the drawing like characters of reference indicate corresponding parts in the different figures.

One of the objections in the standard form of railway box car door seal resides in the fact that by the exercise of a small amount of skill, the seal can be unlocked without injury to the ribbon which extends into the seal, and re-locked, and as a result of this shortcoming in the standard type of seal, a great deal of loss is sustained annually by railway companies through theft.

My invention therefore consists of a seal from which the ribbon cannot be withdrawn without breakage, so that if the contents of a sealed box car are tampered with, the fact is obvious through the condition of the ribbon.

After being formed as by means of dies to the configuration illustrated in the accompanying Figure 3, the portions 43 and 44 are struck into the dished configuration as clearly illustrated in the accompanying Figure 4. The portion 44 is now rotated about the line 45 so that it covers the portion 43 after the conventional locking mechanism 41 (Figure 2) has been positioned within the portion 43. The two opposite edges 46 are then beaded around the edges 47 and after this has been done, the ribbon 42 is inserted through the aperture 48, which it will be noted is formed at an angle as clearly illustrated. When the ribbon 42 is brought around, the lateral slot 49 will be coincident with the above mentioned skewed aperture or slot 48. After passing through the slot 48, the ribbon 42 proceeds along to emerge from a slot 50 extending along the edge between the sides 51 and 52 of the portion 44, this slot preferably being formed after the portions 43 and 44 have been struck, for which reason I have not illustrated the same in the accompanying Figure 3.

Since various modifications can be made in the above invention, and many apparently widely different embodiments of same, made within the scope of the claim without departing from the spirit and scope thereof, it is intended that all matter contained in the accompanying specification shall be interpreted as illustrative only and not in a limiting sense and, I desire only such limitations placed thereon as are specifically expressed in the accompanying claim.

What I claim as my invention is:

A housing and dependent ribbon for the locking mechanism of box car seals, said housing and ribbon being formed from a one-piece patterned blank, one end of said blank being struck into a pair of adjacent dished forms in alignment with the longitudinal axis of the blank to constitute inner and end forms, said end form being provided with two slots extending normal to the said longitudinal axis, the first of said slots being situated medially of the top surface of said form and skewed when viewed in cross-section, the second slot extending along the edge of said top surface, said end form covering said inner form to constitute a hollow housing containing said locking mechanism, said ribbon extending along one side of said end form and also thereover to proceed through said slots, said ribbon being also provided with a slot designed to align and be coincident with said first slot, the free end of said ribbon being designed to extend through said coincident slots and into the interior of said hous-
